(57) CLAIM

I claim the ornamental design for an artificial grass utility mat with handles, as shown and described.

DESCRIPTION

FIG. 1 is a perspective view of the artificial grass utility mat with handles shown in a closed or folded position;

FIG. 2 is a top plan view of the artificial grass utility mat with handles shown in an open or unfolded position;

FIG. 3 is a front elevation view of FIG. 2, wherein the opposite rear elevation view is identical;

FIG. 4 is a side elevation view of FIG. 2, wherein the opposite side elevation view is identical; and,

FIG. 5 is a bottom plan view of FIG. 2.
